United States Patent Office.

ALFRED D. FOX, OF OIL CITY, PENNSYLVANIA.

Letters Patent No. 71,598, dated December 3, 1867.

IMPROVED RAILROAD-JACK.

The Schedule referred to in these Letters Patent and making part of the same.

TO ALL WHOM IT MAY CONCERN:

Be it known that I, ALFRED D. FOX, of Oil City, in the county of Venango, and State of Pennsylvania, have invented a new and useful Improvement in Railroad-Jacks, of which the following is a full, clear, and exact description, reference being had to the accompanying drawing, which makes part of this specification, and which represents a view in perspective of my improved jack.

It is the object of my invention to provide a cheap, portable, simple, and effective device for lifting or straightening railway-tracks; and to this end the improvement herein claimed consists in providing the lifting-screw with a swivelled hook, which grasps the under side of the rail without obstructing the sight along the rail, and mounting its nut on a tripod with pivoted arms, so arranged that the jack can be adjusted to rest on uneven ground, as hereinafter more fully shown.

In the accompanying drawing, the lifting-screw A is shown as mounted in a nut or box, B, supported upon three legs C, pivoted in sockets in projecting wings I on the nut. The ends of the legs, it will be observed, project into their sockets, and are intended to turn in close contact with the walls of the cavities, which thus receive part of the lifting strain, and relieve the journals or pivots of the legs from strain. The legs are formed with broad feet K, to prevent sinking into soft ground. A hook, E, is attached to the lifting-screw by a swivel or link, D, which allows it both to oscillate or swing freely and to turn axially.

In applying this jack, two of the legs may be placed outside of and parallel to the rail to be lifted. The third one may be held up until the hook is placed under the rail, when it may be rested on the ground inside the rail, that is, between the two rails. By inserting an ordinary handspike or crow-bar, F, such as all track-gangs use, in the hole in the top of the screw, and turning it in the proper direction, the rail and cross-ties are lifted to the required level, and then held there until the earth is rammed beneath them. As the hook grasps the bottom of the rail only, the workman can sight along the top of the rail while it is being lifted, and thus secure its proper adjustment. It is obvious that, by resting the feet on the cross-ties, and working the screw, the rail and spikes will be drawn away from the ties.

I am aware that a lifting-jack, having four legs rigidly attached to the nut, and united at their bottom in pairs, has been used, and therefore do not claim broadly a portable jack, mounted on legs, which straddle the rail; but having thus described the construction and operation of my improved jack, what I do claim therein as new, and desire to secure by Letters Patent, is—

The combination, with the lifting-screw carrying the swivelling-hook which grasps the rail from beneath, of the nut or box mounted on the independent legs, when the several parts are constructed and arranged for joint operation, as and for the purpose described.

In testimony whereof, I have hereunto subscribed my name.

ALFRED D. FOX.
